UNITED STATES PATENT OFFICE.

HENRY W. ROBERTS, OF CHEBOYGAN, MICHIGAN.

HOLDBACK FOR VEHICLE-POLES.

SPECIFICATION forming part of Letters Patent No. 444,305, dated January 6, 1891.

Application filed April 14, 1890. Serial No. 347,842. (No model.)

To all whom it may concern:

Be it known that I, HENRY W. ROBERTS, of Cheboygan, in the county of Cheboygan and State of Michigan, have invented a new and 5 useful Improvement in Adjustable Hold-backs, of which the following is a full, clear, and exact description.

My invention relates to improvements in adjustable holdbacks for vehicle-poles; and 10 the object of my invention is to provide a simple, durable, and efficient device that may be applied to all sorts of vehicle-poles, and that may be easily adjusted thereon, thereby providing means for bringing animals of varying 15 size into the same relation to the load without changing the length of the harness-tugs.

To this end my invention consists in the combination, with a pole, of a pole-iron having a raked surface, and a holdback having 20 a corresponding surface and means for adjustably attaching a holdback to the pole-iron. This construction will be hereinafter fully described, and specifically pointed out in the 25 claims.

Reference is to be had to the accompanying drawings, forming a part of this specification, in which similar letters of reference indicate corresponding parts in all the figures.

30 Figure 1 is a vertical longitudinal section of the device as applied to a vehicle-pole. Fig. 2 is an inverted plan view of the same with a portion broken away to show the slot in the pole-iron, and Fig. 3 is a vertical cross-section on the line $x-x$ of Fig. 1.

The pole-iron B is attached to the pole A in the usual manner, so that the under surface of the pole-iron will be flush with the under surface of the pole. Upon the upper 40 surface of the pole-iron B is a thickened portion B', having transversely-ranging ratchet-teeth a , said thickened portion having side flanges b , which inclose the said teeth. The pole-iron B is also provided with a longitudinal slot B², which extends through the under member of the pole-iron and aligns vertically with a recess A', formed in the pole A.

The holdback consists of the horizontal base-plate C, which fits between the flanges b of 45 the pole-iron B, and which has upon its upper surface projecting teeth d , which engage with the teeth a of the pole-iron B. The plate C is

also provided with a vertically-extending portion C', which is braced by a rearwardly-curved member C², which is united to the base-plate at its rear end. 55

The holdback is held in position upon the pole-iron B by a bolt e , which projects through a perforation g in the plate C and through the slot B² of the pole-iron B into the recess A' 60 of the pole A. The bolt e is provided at its upper end with a wide head e' , which projects beyond the edges of the slot B² and engages the upper surface of the pole-iron B. The bolt e is provided upon its lower end with a 65 suitable thumb-nut f , by which it is held in position. The bolt e is also provided with a transverse perforation, through which a key f' is passed to prevent the thumb-nut f from loosening. 70

The device is operated as follows: The vertical portion C' projects at right angles from the pole A, and the neck-ring of the yoke will bear against the said portion in the usual manner. To adjust the holdback upon the 75 pole, the nut f is loosened and the plate C moved backward or forward into a desired position, when the nut f is tightened and the holdback thus held in place.

It will be readily seen that the device may 80 be applied to any sort of pole, either for a vehicle or for agricultural implements of the various kinds.

Having thus fully described my invention, I claim as new and desire to secure by Letters 85 Patent—

1. The combination, with a slotted pole-iron, of a holdback engaging the pole-iron and provided with an aperture, and a bolt passing through the slot of the pole-iron and 90 the aperture of the holdback, substantially as described.

2. The combination, with a pole-iron slotted longitudinally and provided with ratchet-teeth, of a holdback apertured and provided 95 with ratchet-teeth engaging the ratchet-teeth of the pole-iron, and a bolt passing through the slot of the pole-iron and the aperture of the holdback and locking the parts together, substantially as herein shown and described. 100

3. The combination, with a pole and a longitudinally-slotted pole-iron attached thereto, having side flanges and teeth between the flanges, of a holdback adapted to fit between

the flanges of the pole-iron and having teeth to engage the teeth of the pole-iron, and a bolt passing through the holdback and pole-iron, substantially as described.

- 5 4. A holdback for vehicle-poles, consisting of a longitudinally-slotted pole-iron having side flanges and teeth between said flanges, a plate adapted to fit between the flanges, having teeth to engage the pole-iron teeth and 10 having a vertical projection, and a fastening-bolt, substantially as described.

5. The combination, with the pole A, hav-

ing a recess A' therein, and the pole-iron B, having teeth *a* and flanges *b* thereon and the longitudinal slot B² therein, of the plate C, having teeth *d* and a vertical projection C' thereon, and means, as bolt *e* and nut *f*, for attaching the plate C and pole-iron B together, substantially as described. 15
